UNITED STATES PATENT OFFICE

ARTHUR P. HOLDEN AND PHILIP MORGAN, OF TORONTO, ONTARIO, CANADA

ELECTRIC CIRCUIT MAKER AND BREAKER

Application filed June 29, 1925. Serial No. 40,340.

The principal objects of the invention are, to eliminate the possibility of flooding oil in furnaces, in the event of the failure of the ignition, and to devise a very simple and 5 positive form of mechanism for automatically cutting out the control of the motive power.

The principal feature of the invention consists in the novel construction of a casing pivotally mounted on the overflow pipe from the 10 furnace in which a float mechanism is operatively connected with an electric cut out.

In the drawings, Figure 1 is a perspective view of our automatic cut out device shown in the closed position of the switch.

Figure 2 is an enlarged longitudinal vertical mid-section through the device as shown in Figure 1.

Figure 3 is a perspective view of the cut out shown in its tilted position for draining.

In the operation of oil burning furnaces where the oil is fed by means of a power-operated pump, it is necessary to provide an automatic means of cutting out the pump in 25 the event of the ignition failing and it is also necessary to provide means for emptying the oil from the apparatus, so that it may be refilled, and, it is further imperative that such apparatus cannot be left in an inoperable 30 condition.

In the construction herein shown the overflow pipe 1 which leads from the furnace is connected to a suitable pan or other receiver that will catch the oil from the burner nozzle 35 if it is not being ignited.

The pipe 1 leads outside of the furnace and extends into a casing 2 the details of which form the subject matter of a separate application Serial No. 397,048, filed October 3, 40 1929, which is pivotally mounted upon a pin 3 extending through the pipe close to its outer end and through the lugs 4 in the sides of the casing. The said casing is formed with a substantially cylindrical well portion 5.

The sides of the lugs 4 form a lip 6 which fits around the underside of the pipe 1 and connects with the sloping spout-shaped portion 7.

A cover 8 closes the top of the well 5 and 50 is provided with an upwardly flaring lip 9

which registers with the side walls of the lugs 4 and allows the casing to be tipped upwardly to the position shown in Figure 3 when said lip engages the top of the pipe 1 and arrests the further movement. 55

Upon the cover 8 is arranged a pair of upwardly extending standards 10 between which by the lower end is pivoted a rocker arm 11.

The long end of the rocker arm extends 60 over an opening 12 arranged centrally above the well 5 and is pivotally connected to the jaw-shaped stem 13 of the float 14 arranged within said well.

Between the upper ends of the standards 10 65 is pivotally mounted a part-cylindrical casting 15 in which is secured a sealed tube 16 containing a quantity of mercury.

A pair of electrical contacts 17 are secured in one end of the sealed tube 16 and are connected to the wires 18 leading in from the 70 motor control circuit.

The mercury in the tube is adapted to form an electrical connection between the contacts when the tube is tilted in the position shown 75 in Figures 1 and 2.

The tube holder 15 is provided with a fork lug 19 arranged centrally of the length thereof and a spur 20 extending upwardly from the rocker arm 11 engages said fork lug and 80 when the float is in its lowermost position said spur holds the tube tipped with the contact end down as shown particularly in Figure 2.

In the event of oil escaping from the furnace and flowing through the pipe 1, it flows into the well 5 and lifts the float. The lifting of the float tilts the rocker arm 11 on its pivot and causes the mercury to flow to the opposite end, thereby breaking connection between the 85 electrical contacts 17. As long as the float remains raised it will be impossible for the motor to be again started.

A stop lug 21 is arranged on the arm 11 to limit the movement of the switch tube. 90

A spring plunger 22 is arranged in the cover 23 closing in the electrical switch so that if it is desired to break the circuit to the motor at any time, it may be done by 95 pressing down upon the plunger. 100

When the device has operated automatically to cut off the electrical circuit, it is necessary to drain the oil from the well and this is accomplished by the very simple act of tilting the casing 2 upon its pivot allowing the oil to flow therefrom out of the spout 7.

The lip 9 prevents the casing from being tipped past the centre of gravity so that if it is released, it will drop back of its own weight to its normal position and the weight of the float, being unsupported by oil in the well, operates the rocker arm to throw the switch into the position shown in Figures 1 and 2, when it is ready to again operate.

15 It will be seen that if oil has been allowed to flow to the safety switch herein described the motor cannot be turned on and run without cleaning out the well and in emptying the well it cannot be left in an inoperative position.

What we claim as our invention is:—

1. In an electric circuit maker and breaker, the combination with a rigid overflow pipe, of a casing adapted to receive the discharge 25 from said overflow pipe, a float in said casing, a cover closing the casing and having a rigid support extending thereabove at one side of said casing, an arm pivotally mounted on said support and having one end extending over said float and pivotally connected therewith and having a stop extension at the other end adapted to engage said cover to limit the movement of the arm, and a tilting mercury tube switch pivotally mounted at 30 the upper end of said rigid support with its axis spaced above the axis of the arm and being operatively connected with said arm.

2. In an electric circuit maker and breaker, the combination with a rigid overflow pipe, 40 of a casing adapted to receive the discharge from said overflow pipe, a float in said casing, a cover closing the casing and having a rigid support extending thereabove at one side of said casing, an arm pivotally mounted on said support and extending over said float and pivotally connected therewith, a projection on said arm above its pivotal mounting, and a mercury tube mounted on a pivot spaced directly above the pivotal mounting of said 45 arm and having a notched extension operatively engaged from below by the projection on said arm.

3. In an electric circuit maker and breaker, the combination with a rigid overflow pipe, 55 of a casing adapted to receive the discharge from said overflow pipe, a float in said casing, a cover closing the casing and having a rigid support extending thereabove at one side of said casing, an arm pivotally mounted on said support and having one end extending over said float and pivotally connected therewith, and having a stop extension at the other end adapted to engage said cover to limit the movement of the arm, a tilting mercury tube switch pivotally mounted at the 60

upper end of said rigid support with its axis spaced above the axis of the arm and being operatively connected with said arm, a hollow cover mounted on the aforesaid cover and enclosing the operating members, a plunger 70 slidably mounted in the top of said hollow cover directly over one end of said mercury tube and adapted when depressed to engage and tilt the tube to break the circuit, and a spring normally retaining said plunger out 75 of engagement with the tube.

ARTHUR P. HOLDEN.
PHILIP MORGAN.
